DESIGN FOR A COMBINATION PHONOGRAPH
AND RADIO CABINET

Maurice S. Eisman, Philadelphia, Pa.

Application September 30, 1941, Serial No. 103,578

Term of patent 14 years

To all whom it may concern:

Be it known that I, Maurice S. Eisman, a citizen of the United States, residing at Philadelphia, in the county of Philadelphia and State of Pennsylvania, have invented a new, original, and ornamental Design for a Combination Phonograph and Radio Cabinet, of which the following is a specification, reference being had to the accompanying drawing, forming part thereof.

Fig. 1 is a front elevational view of a combi-

nation phonograph and radio cabinet, showing my new design;

Fig. 2 is a side elevational view;

Fig. 3 is a top plan view; and

Fig. 4 is a top perspective view thereof.

I claim:

The ornamental design for a combination phonograph and radio cabinet, as shown.

MAURICE S. EISMAN.
